UNITED STATES PATENT OFFICE.

TADAO MATSUSHIMA, OF KANAGAWAKEN, JAPAN.

APPARATUS FOR ELECTROLYZING SALT SOLUTIONS.

1,368,955.

Specification of Letters Patent. Patented Feb. 15, 1921.

Application filed March 18, 1918. Serial No. 223,180.

To all whom it may concern:

Be it known that I, TADAO MATSUSHIMA, a subject of the Emperor of Japan, residing at No. 599 Midoricho Shichome, Ashi-
5 garagun, Kanagawaken, Japan, have invented certain new and useful Improvements in Apparatus for Electrolyzing Salt Solutions, of which the following is a specification.

10 This invention relates to an apparatus for electrolyzing salt solution by a mercury process, in which the inner surface of a porous bottom of an inner tank is covered by a thin layer of mercury short circuited
15 to cathode pole introduced therein, and this tank is arranged within an outer tank having an anode pole. The bottom of the inner tank is spaced away from the bottom of the outer tank, so that caustic soda so-
20 lution in the inner tank and salt solution in the outer tank are perfectly separated from each other by means of the said layer of mercury, whereby sodium amalgam is produced on the lower surface of the mer-
25 cury layer, which, passing through the layer, comes to the upper surface thereof and is decomposed to produce caustic soda therein. The object of the invention is to greatly decrease the quantity of mercury
30 required, to avoid the necessity of circulating the amalgam and accordingly to save the power for its circulation, thus eliminating the loss of mercury, which necessarily arises in the circulation of mercury in the
35 known method, by preventing its oxidation; in short, to produce a pure and concentrated product with far better efficiency of working current.

An accompanying drawing shows a sec-
40 tional elevation of an apparatus according to this invention in which A is an outer tank, B an inner tank, C the porous bottom of the inner tank, D an anode pole, E a mercury layer, F a cathode pole, G
45 salt solution, H caustic soda solution, I water inlet, J delivery for caustic soda so-
lution, K delivery for hydrogen gas, L de-
livery for chlorin gas. Inlet and outlet
50 for salt solution are omitted in the draw-
ing.

The invention more specifically relates to improvements in an apparatus for the electrolysis of salt solution according to the well-known mercury process, which is re-
55 commended, among hitherto known proc-
esses for producing caustic soda, chlorin

and hydrogen by electrolysis of salt solu-
tion, to give the purest and most concen-
trated product with the best efficiency of
working current. A defect in the hitherto 60
known mercury process resides in the fact
that, it requires a great quantity of mer-
cury which is very expensive. Moreover,
it requires great power for the necessary
circulation of the amalgam produced and 65
loss of such mercury cannot be avoided
during the said circulation.

According to this invention, these draw-
backs are all eliminated. For this purpose
an apparatus according to this invention 70
comprises, as shown, an outer and an inner
tank. The latter is provided with a cathode
and the former with an anode. The bot-
tom of the inner tank consists of porous
material which can support mercury and 75
the upper surface of the bottom is covered
with a thin horizontal layer of mercury,
which in this invention is short circuited
to the cathode. The inner tank is also
suitably provided with supply for salt so-
lution, deliveries for salt solution, caustic
soda solution and for gases. Current passes
from anode, through salt solution to the
lower surface of the bottom of the inner
tank, the upper surface thereof, mercury 85
layer and then the majority of it through
caustic soda solution to cathode, and partly
through short circuit directly to cathode.
This layer of mercury separates both solu-
tions horizontally and the amalgamation is 90
produced on the lower surface thereof while
the recovery of the mercury is completed
on the upper surface. Therefore the mer-
cury according to this invention performs
a simultaneous double action, so that no 95
additional mercury is required. In the ap-
paratus used heretofore a certain quantity
of mercury is required in the recovering
chamber in addition to the quantity of mer-
cury required in the amalgamation cham- 100
ber. Therefore even, considering only this
point, the quantity of mercury required in
this apparatus is decreased by half as com-
pared with the known ones. Moreover, in
the known apparatus for the mercury proc-
ess, because amalgam produced on the up-
per surface of the mercury has less specific
gravity than the mercury itself, said amal-
gam floats upon the surface. Therefore,
unless one is satisfied with a small per- 105
centage of sodium content in the amalgam,
the apparatus known heretofore has a great

drawback. In contradistinction to this, in the present apparatus, the amalgam produced on the lower surface of the mercury layer immediately passes through the mercury and comes upon the upper surface thereof. Therefore there is no hindrance in the amalgamation even with a high percentage of sodium content.

The fact that the required quantity of mercury is small in this apparatus, is based upon not only the double action of the surfaces of the mercury, but also upon the saving of part of the mercury which otherwise flows through the transmitting mercury circulation tubes or pumps. The reason for this, is that mercury in this invention can be recovered from amalgam in one and the same position. Moreover, because mercury does not flow and the amalgam produced on the lower surface thereof floats to the upper surface and is recovered at once, the thickness of the layer can be greatly reduced. The smaller the thickness of the mercury layer, the less time will be required from amalgamation to recovering and accordingly the working current may be decreased. This invention does not relate to the so-called partition process but solely to the mercury process and therefore the porous bottom of the inner tank acts only to support the mercury, and the separation of the two liquids is made by the mercury itself. Therefore, the separation of the two liquids is perfectly achieved the same as in the other mercury process and a pure and concentrated product can be equally obtained. The porosity of the bottom of the inner tank permits the passage of the amalgam therethrough. The purpose of short circuiting the cathode and mercury layer in the inner tank is to prevent oxidation of mercury which may occur when amalgam to be decomposed is insufficient as compared with the quantity of current passing through the inner tank. An ample space is provided between the bottoms of the two tanks for increasing the sectional area of electrolyte in order to decrease its electric resistance.

The working of this apparatus is as follows. The outer tank is filled with satu-

rated salt solution and the inner tank with dilute caustic soda solution, a circuit being thus closed between the tanks, two electrodes and a source of direct current. Chlorin gas generated in the anode can not dissolve in the concentrated salt solution, and it is therefore permitted to escape from the gas outlet. Sodium produced on the lower surface of the mercury layer is amalgamated immediately. This amalgam floats up to the upper surface of the mercury layer and produces caustic soda therein. When the caustic soda solution is suitably concentrated, it is taken out of its outlet and water is supplied, the salt solution being always maintained in concentrated state. Care must be taken during the working to maintain the level of the caustic soda solution always higher than that of water. One can thus prevent salt solution from flowing into the inner tank.

I claim:

1. An apparatus for electrolyzing salt solutions, comprising an outer tank having an unobstructed lower portion and containing a salt solution, an anode pole extending into said salt solution, an inner tank located in the first tank and containing a caustic soda solution, a porous imperforate bottom carried by the inner tank and spaced away from the bottom of the outer tank, a thin horizontal layer of mercury supported by the porous bottom, and a cathode pole extending into said caustic soda and in electrical engagement with said mercury layer. 75
2. An apparatus as defined in claim 1, in which the first tank is provided with a chlorin gas outlet. 80
3. An apparatus as defined in claim 1, in which the inner tank is provided with outlets for caustic soda solution and hydrogen gas, and an inlet for water. 85 90

In testimony whereof I have hereunto set my hand in presence of two subscribing witnesses.

TADAO MATSUSHIMA.
